Arthur B. Jenkins,
ATTORNEY.

UNITED STATES PATENT OFFICE.

OSCAR H. LUDEMAN, OF GLEN RIDGE, NEW JERSEY.

TEMPERATURE ALARM.

Application filed December 20, 1921. Serial No. 523,792.

To all whom it may concern:

Be it known that I, OSCAR H. LUDEMAN, a citizen of the United States, and a resident of Glen Ridge, county of Hudson, and 5 State of New Jersey, have invented a new and Improved Temperature Alarm, of which the following is a specification.

My invention relates to the class of devices that are employed to denote a certain 10 stage in temperature, my improved device being especially applicable for denoting an excessive rise in temperature as in an engine, and an object of my invention, among others, is to provide a device that is extremely simple in construction and effective 15 in operation, to produce an audible signal.

One form of my signal device embodying my invention and in the construction and use of which the objects herein set out, as 20 well as others, may be attained is illustrated in the accompanying drawings, in which—

Figure 1 is a view in side elevation of a gas engine showing one means for attachment of my improved signaling device 25 thereto.

Figure 2 is a view in side elevation of my improved signal.

Figure 3 is a view in central vertical section through my improved signaling device 30 with inner members broken away to show construction.

Figure 4 is a view in cross section on a plane denoted by the dotted line 4—4 of Figure 3.

In the accompanying drawings the numeral 5 indicates a gas engine of any suitable construction and comprising a cylinder head 6 that is provided with the usual 35 chambers for water or similar cooling medium, which chamber communicates as by a connection 7 with a radiator 8, the engine being located, as in a common form of construction of motor vehicles, between the radiator 8 and a dash-board 9.

My improved signaling device may be attached in any suitable location where it will receive the heat from the engine, in the preferred arrangement of installation my improved signal being so attached 45 that it will receive the water or other cooling medium used in the engine. The device may be arranged to receive such cooling medium directly from one of the passages containing such medium, or it may be supported as on the dash-board 9, and as 50

illustrated in dotted lines in Fig. 1, with an extension to the water jacket of the engine by means of which the device will be supplied with a cooling medium.

In that arrangement as illustrated and described herein my improved signal is attached directly to the cylinder head 6 as by means of a threaded nipple located in a threaded hole extending into the water chamber in the cylinder head. This device 60 comprises a shell 10 having a threaded nipple 11 as a means for securing the shell in place. This is preferably of angular shape as at 12 as a means for securing it in place as by means of a wrench or other 65 suitable tool. In this manner the shell is adapted to receive within its interior the water or other cooling medium directly from the engine. A cap 13 comprises a portion of the shell, this cap being secured in 70 place in any suitable manner, as by spinning the upper edge of the shell into a groove in the edge of the cap, a support 14 rising from the cap a short distance, and as 75 illustrated in Fig. 3 of the drawings. A bell 15 of any suitable form rests upon the support 14 and is easily movable thereon except when held from such movement, in the structure herein shown this bell being held 80 from such movement when the temperature 85 of the engine and consequently of the water or other cooling medium within the shell is within safe limits.

To affect this purpose I employ a thermostat that may be of any ordinary construction, that herein shown comprising a case 16 that contains, as is common in devices of this sort, ether, alcohol, or other suitable material, that will operate under 90 changed temperature conditions to actuate a controller 17, this controller being of bellows shape and that will readily contract and expand under the changing temperature conditions of the material within the case. In adapting this thermostat for 95 operation as embodied in my improved signal a controller rod 18 is secured to the bottom of the controller 17, extending upwardly therethrough and having at its upper end a controller head 19, positioned to 100 overlie the upper end of the bell 15, the rod 18 extending through an opening in this end of the bell, which opening is of a size considerably larger than that of the rod, so that the latter will not, when the head 110

19 is raised from the bell, interfere with the free swinging movement of the bell upon the support 14.

The operation of this device will be readily understood, it being noted that as the heat of the engine increases the temperature of the water therein will rise and this will be communicated to the water in the interior of the shell 10 and thence to the liquid 10 within the case 16. This will operate to contract the controller 17 thereby gradually lifting the controller head 19 from engagement with the bell, and the parts will be so arranged that when the heat reaches a 15 dangerous point the contraction of the controller will be sufficient to raise the head 19 enough to permit the bell to swing so that its lower end will engage the sides of the shell 10 and thereby produce an audible 20 alarm. The vibration of the vehicle by which the bell is carried will be sufficient to cause the bell to be swung so that it will make contact with the shell 10 whenever the head 19 is raised enough for this purpose. 25

I claim—

1. A signal comprising a hollow support, a sounding device loosely mounted on said support for movement thereon to sound an 30 alarm, a device movably affected by changes in temperature and located within said support, and a controller operatively connected with said device and with said sounding device to control the movements of the latter.

2. A signal comprising a hollow support adapted to receive a fluid, a sounding device loosely mounted on said support for movement thereon to sound an alarm, a device movably affected by changes in temperature and located within said support to be affected by the temperature of the fluid therein, and a controller operatively connected with said device and with said sounding device to control the movements 45 of the latter.

3. A signal comprising a hollow support, a sounding device loosely mounted on said support for movement thereon to sound an alarm, a device movably affected by changes 50 in temperature and located within said support and comprising a rod extending therefrom, and means on said rod to engage said sounding device to control the movements thereof.

4. A signal comprising a hollow support, a sounding device loosely mounted on said support, a device movably affected by changes in temperature and located within 55 said support and including an expansible

and contractible member, a rod extending 60 from said member to be actuated thereby, and a head on said rod positioned to engage said sounding device to control its condition as to movability or immovability.

5. A signal comprising a shell, a support 65 rising from said shell, a sounding device loosely mounted on said support, a device movably affected by changes in temperature and located within said shell and including an expansible and contractible member, and a controller operatively connected with said member and positioned to engage said sounding device to control its condition as to movability or immovability.

6. A signal comprising a hollow support 75 adapted to receive a fluid, a sounding device loosely mounted on said support, a device movably affected by changes in temperature and located within said support and rigidly secured thereto and including an expansible 80 and contractible member, a rod rising from the bottom of said member through said support and said sounding device, and a head on said rod positioned to control the movements of said sounding device. 85

7. A signal comprising a hollow support having means for attachment to the wall of a water chamber to receive fluid therefrom, a sounding device loosely mounted on said support, a device movably affected by 90 changes in temperature and located within said support and comprising an expansible and contractible member and a controller operatively connected with said member and positioned to engage said sounding device to control its movements. 95

8. A signal comprising a portable traveling support, a signal device loosely mounted on said support for movement thereon to sound an alarm, a device movably affected by changes in temperature and a controller operatively connected with said device last mentioned and with said sounding device to hold the latter against movement on its support and to permit such movement. 100

9. A signal comprising a hollow support, a sounding device loosely mounted to move independently of said support to sound an alarm, a device movably affected by changes in temperature and located within said support and including an extensible and contractible member, a rod extending from said member to be actuated thereby, and a head on said rod positioned to engage said sounding device to control its condition as to movability or immovability. 110

OSCAR H. LUDEMAN.
